UNITED STATES PATENT OFFICE.

GEORGE E. SMITH, OF EXETER, NEW HAMPSHIRE.

BURNISHING-MACHINE.

SPECIFICATION forming part of Letters Patent No. 537,728, dated April 16, 1895.

Application filed March 21, 1894. Serial No. 504,540. (No model.)

To all whom it may concern:

Be it known that I, GEORGE E. SMITH, a citizen of the United States, residing at Exeter, in the county of Rockingham and State of New Hampshire, have invented certain new and useful Improvements in Burnishing-Machines; and I do hereby declare the following to be a full, clear, and exact description of the invention, such as will enable others skilled in the art to which it appertains to make and use the same.

My present improvements relate to burnishing machines for use in the manufacture of boots and shoes.

The object is to simplify, cheapen and perfect the construction of machines of this class, and it therefore consists in the construction, arrangement and combination of parts, substantially as will be hereinafter described and claimed.

In the accompanying drawings illustrating my invention, Figure 1 is a front perspective view of my improved burnishing machine. Fig. 2 is a rear perspective view of the same. Fig. 3 is an enlarged sectional plan view showing the mechanism for operating the brush. Fig. 4 is a vertical sectional view of the hollow standard or base and the interior mechanism which is shown in elevation. Fig. 5 is a detail sectional plan view showing the lever and other mechanism for shifting the rotary support which carries the jacking mechanism for the boots and shoes to be burnished. Fig. 6 is a cross section on line $x-x$ of Fig. 5. Fig.

7 is a cross-section on line $y-y$ of Fig. 5. Fig. 8 is an enlarged sectional edge view of the devices whereby the tool carriers are gradually reciprocated during the operation of the machine. Fig. 9 is a cross section on the line $z-z$ of Fig. 8. Fig. 10 is a detail edge view of the horizontal bar which operates in conjunction with the upper portion of the devices shown in Fig. 8. Fig. 11 is a longitudinal sectional view of one of the levers that compose the head of the machine. Fig. 12 is an enlarged sectional detail view of a portion of the clamping or jacking devices for holding the boot or shoe. Fig. 13 is a view of one of the outer heads or castings that supports one end of each of the several levers composing the head of the machine. Fig. 14 is a view of the inner head or casting employed for sup-

porting the other end of each of said levers. Fig. 15 is an edge view of the part shown in Fig. 14. Fig. 16 is a perspective view of a modified form of the jacking mechanism. Figs. 17, 18 and 19 represent a modified form of burnishing tool which may be employed.

Like letters of reference denote like parts in the different figures of the drawings.

A designates the main frame or standard of my improved burnishing machine, which frame or standard may obviously be constructed in any desired manner, having any suitable shape and proportions. It is preferably hollow to allow certain mechanical parts to be accommodated therein, and is provided with a side door A', to permit of access to those parts.

At one side of the lower portion of the bed or standard A, is located a horizontal counter-shaft B supported horizontally in suitable bearings in the standard A and in a bracket B', on the side of said standard A, said counter-shaft B having thereon a fast and loose pulley B³ which is adapted to receive an actuating belt running from any suitable driving power, and said shaft B having also thereon the pulley B² around which passes a belt which runs upward and around a loose pulley F² on the shaft F belonging to the brush-operating mechanism and also around a pulley H' on the shaft H belonging to the mechanism which operates the burnishing tools, both of said pulleys F² and H' being consequently driven by said belt.

The shaft F is supported in horizontal bearings f f', fastened rigidly on the main standard A or formed as a part thereof. See Fig. 3. Parallel to the shaft F is another shaft I, said shaft I having one of its bearings in an upright casting I² which is rigidly mounted upon the shaft F astride of the bearing f, all as clearly shown in Fig. 2, and said shaft I having another bearing near the brush I' in a horizontal sleeve i, which is pivotally supported in the bifurcated end of a rod J, that passes downward through a right-angled socket f² fastened on the adjacent end of the shaft F, the lower end of rod J being enveloped by a spiral spring j which is tensioned between a collar on the end of rod J and the socket f². The shaft I is made in two parts

that are connected together at a point near the casting I^2 , by a knuckle or universal joint I^4 in order that the brush-carrying end of the shaft I may have a certain freedom of movement laterally to the extent permitted by its connection with the spring-enveloped rod J . On the shaft F is a pulley F^8 , made fast with the loose pulley F^2 , and on the shaft I is a pulley I^3 , opposite to pulley F^8 . A belt passes around these two pulleys so that motion is communicated from loose pulley F^8 to shaft I to drive brush I' . On the shaft F is a segment pinion E , see Fig. 2, securely fixed thereon, which is engaged by a segment gear D' carried on the end of lever D , which is fulcrumed on stud d projecting from part f' , see Fig. 3, or some other suitable part of the frame. The opposite end of lever D , as will be seen by referring to Fig. 4, is located within the casing A , and is pivotally attached to the upper end of the connecting rod C , whose lower end is connected to a crank pin on the stud-mounted gear-wheel a , which meshes with a pinion b , on the counter-shaft B . By these connections between the shaft F and the counter-shaft B , it will be seen that shaft F will be rocked alternately in one direction and then in another and this will take place simultaneously with the swift rotary motion imparted to brush I' from the belt connections with shaft I . Securely attached to the shaft F at a point between the casting I^2 and the segment pinion E , is a counterbalancing weight F' . The effect of alternately rocking shaft F will of course be to carry with it the parts that are firmly and rigidly attached to it and since bearing I^2 and socket f^2 are thus attached, the result will be to alternately transfer the shaft I from the position shown in Fig. 2 where it is vertically above the shaft F , to the position shown in Fig. 3, where it is horizontally opposite to it and also to such other positions as it might assume during the oscillations, depending of course upon the size of the segment gears. Pivoted on the socket f^2 is a short lever g , one end of which is attached to the bifurcated upper end of shaft J , while the opposite end carries a weight G . This weight serves to balance the weight of shaft I and to keep the brush I' from dropping off the heel of shoe, when it is operating on the bottom thereof and to sustain the weight of the shaft and keep same from pressing on the shoe when on top. The weight F' counterbalances the entire brush-operating mechanism and keeps its motion steady and uniform. The segment gear connections will cause the brush to run back and forth from one side of the heel to the other about sixty times per minute, while at the same time the brush is rotating about one thousand times per minute in consequence of the actuation of its shaft in the manner I have described.

The horizontal shaft H which we have seen has thereon a drive pulley H' is supported in suitable bearings in the base of a back box or

standard K which is bolted to the top of pedestal A , said standard K being so recessed or otherwise box-shaped as to permit a vertical worm wheel L to be mounted therein on a stud as shown—see Figs. 1 and 8, said worm-wheel being in engagement with and actuated by the worm H^2 on shaft H . In the end of shaft H , opposite that which carries the pulley H' , is an eccentric pin h which operates as a cam. This pin h is located within a vertical slot m in the lower end of a vertical lever M which is fulcrumed near its middle point upon a stud projecting horizontally from the standard K^2 which is bolted to the top of pedestal A , similarly to standard K . See Figs. 1 and 2. At the upper end of lever M is a segment gear M' which engages the teeth of a segment pinion M^3 on the horizontal shaft N , which is journaled in the upper ends of standards K and K^2 and which carries the burnisher mechanism. Thus it will be clearly seen that as the worm-shaft H revolves, the shaft N will be oscillated by the segment gear-90 ing, and the cam movement. Alongside of the standard K and situated opposite to the internal worm wheel L is a parallel vertical lever K' which is supported at its lower end on a stud at the bottom of standard K . See Figs. 1 and 8. The upper end of lever K' is connected to a horizontal rod O —see Fig. 10—which is attached by its angular semi-circular part, to the grooved casting P —see Figs. 14 and 15—which slides upon the shaft N and is a part of the burnisher operating mechanism. The connection between lever K' and rod O is made by a bolt o , passing through lever K' into a split sleeve O' which embraces rod O and is clamped thereto by a bolt and which slides into the upper end of standard K , through a suitably-shaped opening provided therefor by the side of the bearing for shaft N , as shown in Fig. 8. The fulcrum of the lever K' is obviously at its lower end where it is pivoted upon the stud. At a point opposite to the worm-wheel L the lever K' is provided with a slot k . See Figs. 1 and 8. On the face of the wheel L next to slot k , is a slot or guide-way L' across the center of the wheel L , which is preferably formed by flanges on the wheel face. This slot L' receives the square head l of a bolt L^2 which passes loosely through a thimble L^3 that is placed thereon, with a shoulder next to the worm wheel, as shown, said thimble being made as a square block and being situated in the slot k of lever K' . This block or thimble is adapted to slide back and forth in the slot k . A handle L^4 screws upon the end of bolt L^2 and a washer is interposed between the handle and the thimble L^3 . Thus there is a square block to slide in slot k and a washer or shoulder on each side of said slot to keep the block in place. As the worm wheel L revolves, the thimble L^3 will travel back and forth in slot k , and this will oscillate lever K' . If the head l of bolt L^2 is at the center of wheel, then as worm wheel L rotates, lever K'

will remain immovable and will not oscillate. If however we move head *l* along slot *L'* a short distance from center of wheel *L*, then the thimble will travel in slot *k* and the lever *5* will oscillate sufficiently to regulate to the desired degree the position of the burnisher mechanism. Thus by laying hold of handle *L*⁴ and properly adjusting the head *l*, the burnisher mechanism can be adjusted to operate *10* upon heels of any length, shape and size.

I will now describe the burnishing mechanism proper which is located at the top of the machine and which operates the burnishing tools. The shaft *N* has already been mentioned as being journaled in standards *K* and *K*². On this shaft are the two castings *P* and *Q*. See Figs. 13, 14 and 15. *Q* is the front head and *P* is the rear head of the burnisher mechanism. Each of the two heads *P* and *Q* *15* has a general semi-circular form and is provided with a series of radial slots of which there may be any suitable number, corresponding to the number of the levers *R* to be supported therein. These slots may be provided in any suitable way, either by casting lugs upon the head or by casting indentations in the head. The inner head *P* has its slots formed by the lugs *p*, and the outer head *Q* has the radial openings *q*. In the present example of my invention there are five levers *R*, but I do not wish to be restricted to this number. Consequently the heads *P* and *Q* each have five slots in which the five levers *R* are supported in horizontal positions, as *20* shown in Figs. 1 and 2, the lever *R* being shown in detail in Fig. 11. The head *Q* is secured fast upon shaft *N* by means of a set-screw. See Fig. 13. The inner ends of levers *R* are perforated and connected by screws or *25* bolts to the lugs *p* on head *P*, which slide on shaft *N*. Thus it will be seen that the inner ends of the levers *R* are all connected together by the head *P*, while their forward ends are free to slide in the slots *q* of the head *Q*, whenever a longitudinal movement of the levers *R* occurs.

The levers *R* are all similarly constructed and arranged. See Fig. 11. The forward end is split and a screw-bolt serves to draw the *30* halves tightly together so as to clamp, between them, the spindle of the tool-holder *R'*. This tool-holder may obviously be of any desired kind, and being supported as stated, it will be readily adjustable for any size and *35* shape of heel. These tool holders *R'* preferably have a pin in the center to keep the tool from slipping. On the top of each lever *R* is a small pulley *r*, which may be supported on a stud projecting from a lug on the lever as *40* shown in Fig. 11. A cord, belt or strap *n*, passes around all these pulleys *r* and also down over the guide rollers and into the base *A*, where the two ends of belt *n* are fastened to a clamp *n'* made preferably of two pieces with *45* a cap screw in the center to hold them tightly together. In the bottom of base *A* is a horizontal lever *T*, which is hinged at one end to

the wall of base *A* and has its other end projecting through the opposite side of base *A*, see Fig. 1, and carrying an adjustable weight *T'*. A connecting rod *t* connects the lever *T* with the clamp *n'*. Thus the weight *T'* acts to keep the belt *n* at the proper tension. This belt serves therefore as a pressure belt, giving the same pressure upon levers *R* for *50* any size or shape of heel. To reduce or increase the pressure the weight *T'* may be adjusted upon the lever *T*.

The under side of levers *R* is cored out to receive a longitudinal portion of gas pipe *R*², *55* one end of which is bent and passes through the lever *R* so that a flexible tubing *R*⁵ may be connected thereto, while the other end enters a heat chamber *R*³ adjacent to the burnishing tool. This pipe is used only when *60* necessary as the friction from the tool itself generally gives a good deal of heat. The several rubber tubes *R*⁵, see Figs. 1 and 2, connect to a suitable gas cock *R*⁶ on the standard *K* whereby they are all supplied from *65* some suitable source. Each lever *R* has a set-screw *R*⁴ near head *P* to adjust itself with when large heels are being burnished so as to keep the tool from closing down sufficiently *70* far to prevent these large heels from entering the machine.

A variety of tools may be employed with the tool holders *R'* and I do not wish to be restricted to any particular kind. The tool may be made like a spiral spring and formed *75* around the heel as shown in Figs. 1 and 2. The wire employed for this purpose is preferably oval in cross section. With the wire in this shape a fine burnish is given to the heel with a light pressure. The wire is arranged *80* to cover the heel entirely around it. Hence such a burnisher will operate very fast indeed as it has only to run the length of the heel from the top lift to the upper. Instead of the wire burnisher a cast iron or other metallic tool may be employed. An example of such a tool is shown in Figs. 17, 18 and 19. It has a wax chamber containing a supply of wax, a passage for delivering the wax to the heel and a set-screw to adjust the wax. Tools of this *85* kind are made rights and lefts.

The jack frame consists of a hub *U* provided with any suitable number of arms *u* (say four for example) which furnish rests at their ends for the bottoms of the shoe heels, *90* and also with a similar number of jack arms *U'* which carry the jacking or clamping devices for clamping the shoes firmly in position against the arms *u* where they can readily be acted on by the burnishing tools. This *95* jack frame has its hub *U* mounted on a shaft *U*² on which it slides, said shaft projecting horizontally from one side of base *A*. See Fig. 5. A horizontal lever arm *V* which is pivoted at *v* within the base *A* to the wall thereof, *100* projects through the slot *A*² near the top, of base *A*. This lever connects by a rod *V'* with the hub *U*. The operator therefore can by means of the lever *V* shift the hub *U* and con-

sequently the jack frame, back or forth upon the shaft U^2 . This shaft U^2 has a certain number of splines thereon, say four for instance, and these splines are entered by a pin 5 or pins on the hub so that the hub cannot be rotated on shaft U^2 , except when it is at the outermost end thereof and farthest away from the burnisher mechanism. The jacking devices at the end of each jack arm U' are shown 10 in detail in Fig. 12. They consist essentially of a segment gear W on the end of a pivoted arm W' . This segment engages a rack w on a sleeve w' which is split and furnished with a bolt to enable its halves to be drawn together so that it may serve as a clamp to 15 securely hold within it the spindle W^2 which enters the shoe and forces the heel against the arm u as shown in Fig. 1, said end of the spindle W^2 within the shoe, carrying a thimble 20 with a spring therein so as to make it somewhat yielding to allow for the varying of the heel. Obviously the spindle W^2 can by means of the sleeve w' be set for any length of heel. On the side of each arm U' adjoining the jacking 25 devices is a catch device which projects beneath the lever W' and holds the same in the position shown by dotted lines in Fig. 12. This catch consists of a small lever W^3 which operates a pin that projects beneath lever W^3 . 30 This lever has a spring that keeps it in such position that the pin is normally projected at all times. By pressing on the lever however, the pin is withdrawn so that the lever W' can drop into the position shown in Fig. 12, which 35 releases the spindle W^2 from the shoe and is what takes place in unjacking.

w^2 denotes a rubber or elastic bumper for the lever W' to strike when it falls so as to make no noise or jar. As the hub U is 40 mounted on the spindle U^2 as described, it can be readily removed therefrom. Thus the four arm jack can be taken off and one having more or less arms used when desired.

In Fig. 16, I have shown a jack having only 45 two arms. This style of jack is used for wax and bright burnishing and is operated so that while one shoe is being burnished another will be brushed. When there are but two jack arms as in this case a weight, as for instance 50 ball U^4 is fixed below hub U , so as to keep the jack from burning.

Numerous changes in the details of construction may be made without varying from the claims.

Having thus described my invention, what I claim as new, and desire to secure Letters Patent, is—

1. In a burnishing or brushing machine, the combination of a shaft, segment gearing for 60 oscillating it, a loose pulley thereon, a weight likewise thereon which depends from the shaft and serves to counterbalance the entire brush-operating mechanism and also an end socket, a second shaft parallel to the first shaft 65 and supported in a bearing fixed thereon and driven by a belt from the loose pulley, said second shaft carrying a brush and having a

knuckle joint, the brush end of the shaft being carried in a socket supported by a spring-provided rod that is held in the end socket 70 of the first shaft, and a counter-balance weight for brush-shaft socket said weight being carried by a pivoted lever whose other end engages the spring-provided rod, substantially as described.

2. In a burnishing machine, the combination of the worm shaft having a cam at the end, the vertical lever oscillated by said cam, the shaft oscillated by a segment gearing connection with the upper end of said lever, a 80 worm wheel engaging the worm, leverage devices operated by said worm-wheel, and the burnishing mechanism operated by the aforesaid mechanism, substantially as described.

3. In a burnishing machine, the burnisher 85 head consisting of the slotted outer head, the slotted inner head, the series of levers carrying the burnishing tools, said levers being pivoted to the inner head and adapted to slide in the outer head, substantially as described. 90

4. In a burnishing machine, the combination of an oscillating shaft, an outer slotted head fastened thereon, an inner sliding head likewise on the shaft and a series of levers pivoted to the inner head and sliding in the 95 outer head, said levers carrying the burnishing tool, substantially as described.

5. In a burnishing machine, the combination of the burnisher head, consisting of the slotted outer head, the slotted inner head, and 100 the series of levers carrying the burnishing tools, said levers being pivoted to the inner head, and the reciprocating mechanism for the burnisher mechanism, consisting of a slotted lever connected at its upper end there- 105 with, a worm wheel having a slotted face, a worm for actuating said wheel a bolt having a head engaging the slotted face of the worm wheel, and clamping devices for adjustably holding the bolt in the slotted lever, substan- 110 tially as described.

6. In a burnishing machine, the combination of the worm shaft having a cam at the end, a vertical lever oscillated by said cam, the shaft oscillated by a segment gearing connection with the upper end of said levers, a 115 worm wheel engaging the worm leverage devices operated by said worm wheel, the burnishing mechanism which is shifted endwise by said leverage devices, said burnishing mechanism consisting of an outer head fast on the oscillating shaft and an inner head sliding thereon and a series of levers pivoted to the inner head and sliding through the other head, said levers carrying the burnishing tools, sub- 120 substantially as described.

7. In a burnishing machine, a series of longitudinally-movable tool-carriers having their forward ends split to receive and clamp the tool-holders, guides for the tool-carriers pulleys on said carriers, a pressure belt passing around the pulleys and a weighted lever in the base frame to which the belt is attached, 125 substantially as described.

8. In a burnishing machine, the combination of a carrier or carriers for the tools, an inner head which supports said carriers, guides for the carriers, a shaft on which the head 5 slides, mechanism for oscillating the shaft and mechanism for reciprocating the head and the carriers and for regulating the extent of movement thereof, substantially as described.

9. In a burnishing machine, the combination of the burnisher mechanism, consisting 10 of the reciprocating carriers, the inner head to which they are attached, the slotted outer

head which serves as a guide for the carriers, the operating mechanism for the carriers and the jack frame supported upon a central hub 15 and having radial arms, together with clamping devices on said arms, substantially as described.

In testimony whereof I affix my signature in presence of two witnesses.

GEORGE E. SMITH.
